Application May 25, 1932, Serial No. 613,522
Renewed April 13, 1934

14 Claims. (Cl. 199—19)

The present invention relates to improvements in typographical machines and more especially to those of the general class shown and described in U. S. Letters Patent No. 436,532, granted September 16, 1890, wherein character bearing matrices are stored in a magazine or magazines and are delivered therefrom by manipulation of a keyboard and are assembled in lines from which type bars or slugs are cast.

10 Machines of this class as heretofore constructed have been provided with main magazines adapted to handle matrices having the ordinary smaller sizes of newsprint and text faces and also matrices having somewhat larger faces such as those commonly used in display advertising, news headings and the like. In constructing machines of this class for matrices having larger type faces, it has been the practice to employ main matrix magazines of the same conventional 15 trapezoidal shape and size as those used for matrices bearing the smaller type faces, in order to retain the desirable feature of interchangeability of the magazines on the machines and at the same time obviate the expense and difficulties that 20 would be involved in deviating from the standard size matrix distributor and assembling mechanisms directly associated with the magazines.

While this adherence to the conventional elements of the machine and the magazines there- 25 for has practical advantages, it has the disadvantage that the capacity of the machines is limited thereby with respect to the sizes of the type faces on the matrices possible for them to handle. This will be seen from the fact that the 30 usual so-called 90 channel magazine having 91 channels to contain a 90 character matrix font, two channels being provided for the letter *e*, and in which the channels are unequally spaced at both the upper and lower ends to obtain the maxi- 35 mum capacity for the width of the matrices, is limited to matrices having 18 point type faces. In order to enable the magazines to accommodate thicker matrices having relatively larger type faces, so-called 72 channel magazines have been 40 employed, these magazines containing 73 channels to receive 72 character matrix fonts, two channels being provided for the letter *e*, and in these 72 channel magazines, the channels have also been unequally spaced at both the upper and 45 lower ends of the magazines, but notwithstanding the smaller number of different character matrices contained in such magazines, the maximum size full face matrices which it has been possible to store in these magazines is of 24 point size, 50 which is only one standard point size larger than

it has been possible to handle with the 90 channel magazine, although a few 30 point condensed face matrices can be used with the 72 channel magazines. In order to provide for larger face matrices than those which it is possible to handle in the usual 72 channel magazines, magazines having 55 channels to contain 55 character matrix fonts have been proposed, but this great reduction in the number of available characters in such fonts renders such magazines generally impractical and unsatisfactory because the number of different character matrices available in 55 character fonts is insufficient to meet the ordinary requirements unless auxiliary magazines are used in conjunction therewith.

It is well recognized that the most reliable and satisfactory operation of machines of this class is attained by assembling the lines of matrices only from the so-called main magazines which are controlled by the usual main keyboard. Due to the smaller number of characters in the matrix fonts that may be handled in the 72 and 55 channel magazines and the limited sizes of type faces such matrices may contain, the desirable operation of the machine to deliver the matrices from the main magazine or magazines by manipulation of the main keyboard is disturbed to a large extent, since it requires the use of auxiliary magazines in conjunction therewith to carry the additional character matrices needed. Consequently, in the development of machines of this class, it has heretofore been necessary to employ auxiliary or so-called side magazines to contain practically all matrices having type faces larger than 24 points. The assembling of matrices from such auxiliary or side magazines presents the disadvantage, however, of requiring the operator either to control the delivery of the matrices from the auxiliary or side magazine by manipulation of another or auxiliary keyboard or to manipulate special controls to connect the main keyboard to the matrix release devices for the auxiliary or side magazines, and furthermore, the increased distance over which the matrices are required to travel from the auxiliary or side magazines to the assembling point materially retards the speed of composition, disturbs the rhythm of the keyboard operation and moreover frequently causes transpositions of the matrices. Because of these undesirable conditions, it is 105 advantageous to avoid the use of auxiliary or side magazines as much as possible, apart from the further disadvantage that machines having such auxiliary equipment occupy much more floor space and are more costly than those containing 110

only main magazines controlled from the usual or main keyboard.

The primary object of the present invention is to materially increase the range of sizes of type faces on matrices that can be made available from main magazines, and to provide for handling 72 character matrix fonts in these magazines having larger type faces than has heretofore been possible, thereby avoiding to a much greater extent the necessity of employing auxiliary or side magazines, particularly for the most frequently used larger type face matrices, such as 36 point and even larger sizes.

A further object of the invention is to provide a combination machine which will have a capacity for 72 character matrix fonts having larger type faces than heretofore and which, at the same time, will employ any of the 90 character matrix fonts in combination therewith, and which will enable matrices from either of such fonts to be delivered under control of the standard 90 character main keyboard and which matrix fonts may be used at will without requiring shifting of the magazines and, if desired, without disturbing the order of the characters from the usual positions they occupy on the standard keyboard.

Accordingly, the present invention provides a matrix magazine constructed on a new plan and related in a new manner to the machine and the parts thereof with which the matrix delivery ends of the magazines usually cooperate. In carrying out the present invention it has been found practical to increase the width of the lower or delivery end of the conventional trapezoidal type of magazine while preferably retaining its present width at the upper end, and to thereby greatly increase its capacity with respect to the sizes or thicknesses of matrices that can be discharged therefrom, the use of such an improved magazine being practical, however, provided such increase in the width of its lower or discharge end is properly disposed with respect to the cooperating elements of the machine such as the matrix receiving throat and assembler entrance and other associated devices, and that these devices are constructed or adapted to effect the proper and necessary cooperation with the widened magazine.

The difficulties overcome by the present invention whereby the above noted objects are attained will be apparent from the fact that it would not ordinarily be possible or practical to employ a magazine of substantially greater width than that of the standard magazine unless the increased width of the delivery end of the magazine is arranged to cooperate with the standard assembler entrance, since any extension of such entrance at its right hand side would result in a longer travel of the matrices from the right hand side of the magazine in order to reach the assembling point and such increased length of travel of such matrices would result in an undesirable reduction in speed of assembly of these matrices over that of the matrices from the left hand side of the magazine and would consequently cause a disturbance of the keyboard rhythm or response and would tend to cause transpositions of the matrices.

According to the present invention, these and other obstacles that have long stood in the way of a departure from the conventional standards of construction are overcome and the range of type sizes of the matrices which can be handled by machines of this class is greatly increased, and moreover, the invention opens new possibilities

for the developments of such machines. For example, by extending the left hand side of the delivery end of a magazine beyond a point vertically above the assembling point of the line while retaining the right hand side of the delivery end of the magazine at its present position or extending it beyond such position although arranging for the thus widened delivery end of the magazine to discharge matrices therefrom within the limits of width of the standard assembler entrance enables machines of this class to be developed so that they will handle matrices having much larger type faces than could otherwise be handled, one of such developments made possible by the present invention being disclosed in one embodiment shown herein, in which the matrix line assembling elevator or other means is movable obliquely instead of vertically as heretofore, thus enabling the magazine to be widened or positioned to even a greater extent toward the left in the machine.

The preferred embodiments of the invention are herein shown and described, but it will be understood that equivalent constructions are contemplated and such will be included within the scope of the claims.

In the accompanying drawings:—

Fig. 1 is a front elevation of a portion of a typographical machine of a well known class and standard construction but embodying the present invention;

Fig. 2 is a side elevation of a portion of the structure shown in Fig. 1 as viewed from the right;

Fig. 3 is a plan view of the improved widened magazine, showing the width or outline thereof in relation to a standard magazine;

Fig. 4 is a view on an enlarged scale of the lower or discharge end of the improved widened magazine;

Fig. 5 is a view, also on an enlarged scale, of the lower or discharge end of a standard magazine; and

Fig. 6 is a front elevation of a portion of a typographical machine containing another embodiment of the present invention.

The improved matrix magazine, designated 1, is preferably constructed with the usual top and bottom plates 2 and 3 having channels 4 extending from top to bottom thereof in converging relation to contain preferably a 72 character font of matrices M, such matrix font comprising sufficient type characters for display composition, the matrices bearing these characters being arranged in the magazine preferably in the same order, reading from left to right, as commonly used for the standard 90 character matrix fonts, as shown in the standard magazine 5 in Fig. 5, although the matrices in the improved magazine may be arranged in some other suitable order if desired. Since the lower or matrix delivery end of the conventional trapezoidal magazines now in use is somewhat narrower than the upper or matrix receiving end, the capacity of these magazines with respect to the size or thickness of matrices that can be discharged therefrom is accordingly restricted, it being understood that the upper or matrix receiving end of such a magazine is capable of handling larger or thicker matrices than will pass out of its delivery end, because of the greater width at the top. According to the present invention, the improved magazine 1 is widened at its delivery end in order to approach as closely as possible the desirable condition that the largest or thickest matrices which

the magazine is capable of handling at its upper end can be delivered from the lower end thereof without increasing the width of the delivery end of the magazine beyond that which has been found practical, the present invention enabling the conventional matrix magazines used on these machines to be constructed on the basis of balance or equality with respect to capacity to receive and discharge matrices.

In order that the greater width of the discharge end of the improved magazine 1 may be coordinated properly with the usual assembling devices of the machine, at least a portion of its increased width is disposed beyond the side or usual terminating point of standard magazines at the left side, so that some of the channels of the improved widened magazine 1, according to the present invention, lie to the left of a vertical plane passing through the normal point of assembly, while at the right side, the magazine 1 extends to or beyond the usual terminating point of magazines at this side of the machine. By thus disposing at least some of the increased width of the magazine 1 toward the left, it is practicable to assemble matrices from magazines of considerably greater width at the delivery end than those heretofore employed without disturbing the rhythm of the keyboard or accuracy of assembly, it being thereby made possible to confine the extremities or lateral limits of the delivery end of the widened magazine substantially within the range or width of the usual assembler entrance for standard width magazines.

While it is intended that one of the improved magazines 1 or a plurality thereof in superposed or column relation may be employed in the machine, a novel arrangement for this purpose being hereinafter described, it is one of the objects of the present invention to provide a machine which will render available matrices having a greater range of type sizes than heretofore in order to more fully meet the modern requirements of composing rooms, wherein much time and expense can be saved by providing for the composition of lines of text matter as well as lines of display type on the same machine. To this end, the improved magazine 1, widened at its delivery end as described above, is arranged above a standard width magazine 5 which may contain either a 90 or a 72 character font of matrices, these magazines being shown mounted in a machine of the so-called mixer type substantially as represented in U. S. Letters Patents No. 1,202,719, granted October 24, 1916, and No. 1,542,774, granted June 16, 1925, to T. S. Homans, and No. 1,607,259, granted November 16, 1926, to E. M. Goodbody. As shown in Fig. 1, the lower or matrix discharge ends of both magazines 1 and 5 communicate with a common set of passages 6 formed by the usual vertical guides or partitions 7 of the assembler entrance of the machine, and although the widened delivery end of the magazine 1 extends laterally to considerable extents beyond the sides of the delivery end of the magazine 5, the delivery end of the magazine 1 is arranged to discharge matrices from all of the channels thereof into the assembler entrance, the upper ends 7a of the guides or partitions 7 being extended upwardly and flared to conform with the widened discharge end of the magazine 1, so that the matrices discharged either from the magazine 1 or the magazine 5 will enter and descend by gravity through the passages 6 and will be deposited on the usual inclined and travelling conveyor belt 8 and conducted by the latter

to the assembler star wheel 9, the latter being located at the assembling point toward the left hand side of the assembler entrance and acting in the usual manner to assemble the matrices in a line in the usual assembling elevator 10. The delivery of the matrices from one or the other of the magazines 1 and 5 may be controlled from the usual main keyboard, at the will of the operator, the magazines as shown in the present instance having escapements 11 and 12 at their delivery ends controlled respectively by sets of vertically movable reeds 13 and 14, and these sets of reeds being actuated from the keyboard by a set of keyboard reeds 15 which are shiftable into cooperation with one or the other set of reeds 13 or 14 by a handle or lever 16 which is pivoted at 17 above the usual main keyboard and is connected by a link 18 to a swinging frame 19 which carries the keyboard reeds 15. The reeds 13 for the escapements of the upper wider magazine 1 which are within the width of the narrower lower magazine 5 extend upwardly through the throats 7b for the lower magazine as shown in said patent to Goodbody, while the reeds of this set for the escapements of the upper magazine which are beyond the sides of the lower magazine extend upwardly past the sides of the delivery end of the lower magazine and directly to such escapements, as shown in Figs. 1 and 2. In the embodiment of the invention shown in Fig. 1, the usual spaceband box 20 is arranged at the left hand side of the assembler entrance and is provided with a vertical chute 21 through which spacebands are delivered to the assembling point.

It would not ordinarily be practical to employ a magazine widened in the manner described in cooperation with a magazine of standard width and with the assembler entrance passages 6 except by extending at least a portion of the widened magazine toward the left, since, if the magazine is widened sufficiently to pass matrices from its delivery end which are of the maximum size or thickness capable of entering the upper end of the magazine and such increased width were applied only at the right hand side of the assembler entrance, the right hand channels in the widened magazine would be too far distant from the assembling point and from the upper end of the usual inclined portion of the matrix delivery belt 8, and furthermore, the guides or partitions 7, in order to receive matrices from the right hand channels in the magazine, would have insufficient inclination to carry the matrices dropping thereon by gravity onto the delivery belt 8, unless the delivery end of the magazine were placed much higher on the machine than usual, which would be objectionable, and the difficulties thus arising could not be overcome since the right hand limit of the assembler entrance has been determined for these machines after long experimentation.

A comparison of the widened delivery end of the magazine 1 shown in Fig. 4 with the delivery end of a standard magazine 5 as shown in Fig. 5 shows that the magazine 1 is widened at its delivery end at both the right and left hand sides beyond the sides of the delivery end of the standard magazine and that such widening of the delivery end of the magazine 1 affords a substantial amount of additional space in which the larger or thicker display matrices may be accommodated, so that fonts of 72 character matrices of much greater size can be employed in the improved magazine, and in fact, the improved

magazine, which is capable of receiving 36 point character matrices at its upper end, is capable of discharging matrices of such size at its delivery end, whereas the magazines heretofore used to contain 72 character matrix fonts were limited to the discharge of 24 point character matrices and, in some instances, certain condensed 30 point matrices.

The hereinbefore described cooperative relation provided between the magazines 1 and 5 and the assembler entrance is accomplished without the necessity of making any major changes in the standard machine, it being made possible by apportioning the increased width of the magazine 1 beyond one or both sides of the standard width magazine 5 and by placing the magazine 1 above the magazine 5. A machine thus equipped with a magazine of standard width and, above it, a magazine of greater width at the delivery end, affords substantial advantages to the user thereof, it being possible, on a single machine so equipped, to compose lines with any size of type face from 5 point to 36 point and even larger condensed faces without employing auxiliary or side magazines, thereby increasing the capacity of the machine with respect to the range of composition and, in consequence, reducing the cost of composition as well as of the equipment in the composing room.

The upper ends of the magazines may be arranged as usual to receive the matrices, after the casts have been made therefrom, from a distributor 22 which may be of the usual well known construction, and if the upper ends of the magazines remain of the usual standard width, the usual distributing mechanism in the machine may be used without change.

Fig. 6 shows another embodiment of the invention which enables a further increase in the width of the magazines and a further extension of the magazines toward the left in the machine which, as hereinbefore pointed out, is most desirable and practical in order to insure accurate assembly of the matrices. According to this embodiment of the invention, a departure is made from the customary vertical alignment of the left hand side of the magazine or magazines with the point of assembly of the lines immediately in front of the assembler star wheel 9, the left side of the magazine in this instance being offset obliquely to the assembling point and the spaceband box and delivery chute therefor being arranged in a corresponding oblique position and the assembling elevator being guided to move in a corresponding oblique path instead of vertically as heretofore.

Whereas, in the arrangement shown in Fig. 1, the left hand side of the magazine 5 lies vertically above the assembler star wheel 9 while the left hand side of the magazine 1 lies to the left of the star wheel the maximum distance possible with the standard vertically disposed spaceband box 20 and its delivery chute 21, the spaceband box 20^a and its delivery chute 21^a in Fig. 6 are disposed angularly or in oblique positions to the left of the assembler star wheel 9, and the left hand sides of the magazines 1^a and 5^a have been extended to the left of the assembler star wheel 9 an amount equal to the total additional width of the magazine 1 over that of the magazine 5, as represented by X and X' in Fig. 3, or, in other words, the total increased width of the magazines, represented by X and X', has all been added only to the left sides of the magazines 1^a and 5^a, such being rendered possible by the oblique ar-

angement of the spaceband box 20^a and its discharge chute 21^a. The usual assembler entrance containing the guides 7^a is of a width to receive matrices from magazines of standard width although said guides are extended toward the left to receive matrices from the left hand sides of the magazines 1^a and 5^a, the right hand sides of these magazines and the assembler entrance preferably occupying the usual positions on the machine. In coordination with the oblique arrangement of the spaceband box and its discharge chute, the assembling elevator 10^a, in this embodiment of the invention, is movable in guides 23 which are preferably arranged parallel to the obliquely arranged spaceband discharge chute 21^a so that the assembling elevator will ascend and descend in a corresponding oblique path. The assembling elevator may be lifted by the usual lift arm 24 at the side of the keyboard 25 and a connecting link 26 which latter is free to swing laterally to conform with the oblique movement of the assembling elevator.

By employing the modified construction shown in Fig. 6, the lower magazine 5 in Figs. 1 and 2 may be of the same increased width as the magazine 1 and, if desired, the increased width thereof may be added only at the left hand side. The advantage of this arrangement is that it permits the construction of machines with two or more magazines containing 72 character display matrix fonts of the larger sizes made possible by the use of magazines widened and disposed on the machine as hereinbefore described. Such machines would have increased usefulness in the field of display composition which at present depends largely upon special display casting machines requiring hand assembly of the matrices instead of the speedy and less costly keyboard assembly and casting on automatic machines.

Obviously the invention may be applied to magazines containing either more or less characters in the fonts than hereinbefore referred to, so that the range of usefulness of the machine is greatly increased and the machine may be adapted to requirements that have heretofore been beyond its reach and could not be realized without extensive and substantial re-design.

We claim as our invention:

1. In a typographical machine having a matrix assembler, and an assembler entrance at one side thereof of a width adapted to receive matrices from the delivery end of a matrix magazine of standard width and direct such matrices to the assembler, a matrix magazine of greater width at its delivery end than that of such standard width magazine for delivering matrices into said entrance, a portion at least of the increased width of the delivery end of such magazine being disposed at the side thereof toward the assembler and said side of the magazine extending laterally beyond a point vertically above the assembler.

2. In a typographical machine having a matrix assembler, and an assembler entrance at one side thereof and leading laterally thereto and adapted to receive matrices from the delivery end of a matrix magazine of standard width and direct such matrices to the assembler, a matrix magazine having a greater width at its delivery end than that of such standard width magazine and having its increased width disposed laterally beyond a point vertically above the assembler at one side and at least to the limit of the standard width assembler entrance at the other side.

3. In a typographical machine having a matrix assembler, and an assembler entrance for direct-

- ing matrices thereto, a matrix magazine of standard width at its delivery end for delivering matrices to said entrance, and a magazine of substantially greater width at its delivery end for 5 also delivering matrices to said entrance, the delivery end of the wider magazine extending laterally beyond a point vertically above the assembler and the corresponding portion of the standard width magazine at the side nearest the 10 assembler being disposed substantially in vertical alignment therewith.
4. In a typographical machine having an assembler, the combination of a matrix magazine of standard width at its delivery end and a magazine 15 of substantially greater width at its delivery end, and an assembler entrance comprising walled passages and an inclined conveyor for receiving matrices descending by gravity therein and directing them to the assembler, the outermost 20 passages of said entrance being common to matrices descending by gravity from the respective outermost sides of either of said magazines for leading said matrices directly to the inclined conveyor.
- 25 5. In a typographical machine having a matrix assembler, the combination of two matrix magazines of different widths at their delivery ends, and an assembler entrance having an inclined conveyor and a series of walled passages adapted 30 to guide matrices descending by gravity therein directly to said inclined conveyor from the full width of either of said magazines.
6. In a typographical machine having a matrix assembler, an assembler entrance at one side 35 thereof and leading thereto for the gravity descent of matrices to the assembler, the combination of two matrix magazines of different widths at their delivery ends and both arranged to discharge matrices into said entrance, the side of the wider 40 magazine delivery end toward the assembler being extended beyond the corresponding side of the narrower magazine delivery end and beyond a point vertically above the assembler.
7. In a typographical machine having a matrix 45 assembler, an assembler entrance at one side thereof for directing matrices thereto, a matrix magazine mounted to discharge matrices into said entrance, the matrix discharge end of said magazine being extended laterally beyond a point vertically above the assembler, and an assembler elevator mounted to receive matrices from the assembler and guided to move obliquely upwardly and laterally from the entrance.
8. In a typographical machine, the combination 55 of a matrix assembler, an assembler entrance extending to one side thereof for directing matrices thereto, a spaceband box offset at the other side of the assembler and having a spaceband chute inclined downwardly and laterally 60 toward the assembler, a matrix magazine having its discharge end extended beyond a point vertically above the assembler and toward the spaceband box, and an assembler elevator mounted to receive matrices from the assembler 65 and guided to move obliquely in a path in substantial parallelism with the inclined spaceband chute.
9. A typographical machine having a plurality 70
- of channelled matrix magazines of different widths at their delivery ends, one magazine having a smaller number of matrix channels contained within the greater width thereof than the number of matrix channels contained within the width of another of such magazines.
10. In a typographical machine having a matrix assembler and an assembling elevator adjacent thereto, a plurality of matrix magazines disposed, at the sides thereof toward the assembler, with their delivery ends extended laterally beyond a point vertically above the assembler, and a spaceband box having a chute inclined downwardly and laterally toward the assembler substantially in oblique alignment with said laterally disposed ends of the magazines and the junction between the assembler and the assembling elevator.
11. In a typographical machine having a matrix assembler and an assembler entrance embodying an inclined delivery belt for directing matrices to the assembler, the combination of a magazine of standard width at its delivery end and adapted to deliver matrices from the entire width thereof directly to the inclined delivery belt, and a magazine of substantially greater width at its delivery end and also adapted to deliver matrices from the entire width thereof directly to said inclined delivery belt.
12. In a typographical machine, the combination of a plurality of channelled matrix magazines of different widths at their delivery ends, one having a smaller number of matrix channels contained within the greater width thereof, than the number of matrix channels contained within the width of another of such magazines, and an assembler entrance comprising an inclined conveyor to receive matrices directly from all of the channels of either of said magazines.
13. In a typographical machine having an assembler, the combination of a matrix magazine of standard width at its delivery end and a magazine of substantially greater than standard width at its delivery end, an assembler entrance comprising two series of walled passages of different widths corresponding to the different widths of the delivery ends of the respective magazines, and a common inclined conveyor for directly receiving matrices descending by gravity through either series of walled passages for leading said matrices to the assembler.
14. In a typographical machine having an assembler, the combination of a matrix magazine of standard width at its delivery end, a magazine of substantially greater than standard width 130 and extended over a portion of the width at its delivery end laterally beyond a point vertically above the assembler, an assembler entrance at one side of the assembler and comprising two series of walled passages each of which series is 135 of a width and extent corresponding to the width and extent of the respective magazine, and an inclined conveyor common to both series of passages for receiving matrices directly from either of said magazines and leading them to the assembler.
